Alors qu'il n'y a pas d'individu qui ne soit pas atteint par l'agent, il existe un seul individu qui n'est pas atteint par l'agent. Cet individu est donc atteint par l'agent, mais il n'est pas atteint par l'agent. C'est donc un individu qui n'est pas atteint par l'agent, mais il est atteint par l'agent. C'est donc un individu qui n'est pas atteint par l'agent, mais il est atteint par l'agent.

UNITED STATES PATENT OFFICE

2,602,569

WALL RECEPTACLE AND DISPENSER FOR GASEOUS MATERIAL

Richard W. Ryan, Brooklyn, N. Y.

Application June 3, 1949, Serial No. 96,916

2 Claims. (Cl. 222—3)

1

This invention relates to a wall receptacle, designed primarily for use in supporting a can or container containing deodorizing material which is released from well known containers of deodorizing material, wherein the deodorizing material is held under pressure and released by the action of a spring-controlled valved nozzle.

An important object of the invention is to provide a wall receptacle of this form, which may be secured within a closet or room in an out-of-the-way place, the receptacle being so constructed that a container of the class described, may be readily and easily placed therein, without the use of tools, the container being securely held within the receptacle, against accidental displacement.

Another object of the invention is to provide means forming a part of the receptacle, for moving the container upwardly within the receptacle, forcing the valve of the container against a stationary stop bar forming a part of the receptacle, unseating the valve and releasing the deodorant to the atmosphere.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawing:

Figure 1 is a perspective view of a wall receptacle constructed in accordance with the invention, the operating lever having been removed.

Fig. 2 is a side elevational view of the receptacle, showing a deodorant container mounted therein, the upper and lower portions of the receptacle or container, being broken away.

Fig. 3 is a fragmental side elevational view of the receptacle with the stop bar of the receptacle in position therein.

Referring to the drawing in detail, the reference character 5 indicates the body portion of the receptacle, which is preferably cylindrical in form, and constructed of any suitable material, preferably plastic.

In forming the particular receptacle as shown in the drawing, the plastic material is molded in such a way as to provide a backing plate 6, with its upper and lower ends 7 and 8 respectively, extended beyond the ends of the body portion 5, where they are provided with openings 9 for the reception of securing nails or screws, not shown. Due to this construction the receptacle may be

readily and easily secured within a closet or room for supporting a container in which deodorizing material is held.

5 Extending upwardly and forwardly from the upper edge of the body portion 5, are lugs 10, which have their forwardly extending portions spaced from the upper edge of the body portion 5 to cooperate with the lugs 11 formed at the ends of the stop plate 12 in holding the stop plate in position on the upper end of the receptacle. The lugs 11 are formed by cutting notches 13 in the ends of the plate 12 adjacent to the forward edge of the plate, the notches being fitted over the lugs 10 of the receptacle and the plate 12 swung downwardly to the position as shown by Fig. 3 of the drawing, whereupon the plate is held against displacement on the upper end of the receptacle.

In order to remove the plate it is necessary to swing the plate upwardly from the position shown by Fig. 3, and then move the plate forwardly away from the lugs 10. This structure provides means for readily and easily securing the container in which the deodorizing material is held.

25 The deodorizing container is indicated by the reference character 14 and is provided with the usual nozzle 15 that is controlled by a spring valve, not shown, the valve being operated by pressure directed to the button 16 that extends above the nozzle 15.

30 above the nozzle 15. On the lower surface of the plate 12, is a wear plate 17 that rests directly on the button 16, as clearly shown by Fig. 2 of the drawing.

35 An opening 18 is formed in the bottom of the receptacle, and this opening has an inclined wall 19 providing a clearance for the lever 20 that is disposed within the opening 18, the lever being formed with a right-angled end 21 that normally rests on the bottom of the receptacle, in position 40 so that when the lever 20 is forced rearwardly, the right angled end 21 will contact the bottom of the container 14, lifting the container within the receptacle and forcing the button 16 against the wear plate 17, opening the valve in the nozzle 45 15 to release deodorizing material under pressure to the atmosphere. When the lever 20 is released, it is obvious that the container will move downwardly and return to its normal position, the valve cutting off the flow of deodorizing material 50 through the nozzle until the lever 20 is again operated.

From the foregoing it will be seen that due to the construction shown and described, I have provided a wall receptacle which may be permanently secured to the wall of a closet or room and

a container in which deodorizing material is held, may be positioned within the receptacle so that the operating lever may be conveniently operated to release deodorizing material into the closet or room area, as desired.

Having thus described the invention, what is claimed is:

1. A wall receptacle comprising a cylindrical body portion having an open upper end and a closed lower end in which a container containing material to be dispensed under pressure is positioned, the material in the container being released through a spring pressed nozzle valve in the upper end thereof, a stop bar removably connected with the receptacle and extended across the open upper end of the receptacle against which the spring valve of the nozzle is moved for actuation, the bottom of the receptacle having an opening engageable with the bottom of the container forcing the container upwardly within the body portion directing pressure to the valve, operating the valve and releasing material through the nozzle.

2. A wall receptacle, comprising a body portion having an open upper end and a closed bottom in

5 which a container containing material under pressure, is positioned, and released by opening a nozzle valve, a lever comprising a member having a right angled end portion, extending through an opening in the bottom of the body portion, the right angled end of the lever being normally spaced from the bottom of the container, said right angled end of the lever being movable into engagement with the bottom of the container elevating the container within the body portion, and a combined removable cover partially closing the open upper end of the body providing a stop against which the valve of the container engages, operating the valve of the container when the container is elevated a predetermined distance, releasing material contained in the container.
